CLAIM

The ornamental design for a sanitary pad, as shown and described herein.

DESCRIPTION

FIG. 1 is a front isometric view of a sanitary pad.

FIG. 2 is a side view of the sanitary pad.

FIG. 3 is a frontal view of the sanitary pad; and,

FIG. 4 is a bottom view of the sanitary pad.

The broken line in FIGS. 1 and 3 represents a feature of the sanitary pad that forms no part of the claimed design.

1 Claim, 4 Drawing Sheets
